UNITED STATES PATENT OFFICE.

FRANÇOIS ADOLPHE CHARLES JEAN OMLOR, OF BONNEVOIE LES LUXEMBURG, GRAND DUCHY OF LUXEMBURG.

FASTENING FOR GLOVES.

SPECIFICATION forming part of Letters Patent No. 249,390, dated November 8, 1881.

Application filed September 16, 1881. (No model.)

To all whom it may concern:

Be it known that I, FRANÇOIS ADOLPHE CHARLES JEAN OMLOR, of Bonnevoie les Luxemburg, Grand Duchy of Luxemburg, have 5 invented a new and useful Improvement in Compound Fastenings for Gloves and other Garments, which is fully set forth in the following specification.

This invention relates more particularly to 10 fastenings for gloves.

It has for its object to enable the article when put on to be fastened easily, quickly, and securely.

Ordinarily it is required to engage a large 15 number of buttons or other fastening devices, or to tighten a long length of lacing—operations requiring considerable expenditure of time, especially when there is a long opening, as in the gloves which cover nearly the entire 20 forearm. To obviate this difficulty, elastic devices which will extend and allow the glove to be drawn on the hand and then contract around the wrist have been used as fastenings for some kinds of gloves; but these are liable to 25 become useless by loss of elasticity, and either are so strong as to require much exertion in putting them on, and when on to exert an uncomfortable pressure upon the wrist, or are so weak as to furnish an insecure fastening. 30 Practically, the non-elastic devices, such as buttons and the like, which can be fastened and unfastened, are found superior to others.

In the present invention the main advantages attending the use of such non-elastic devices are preserved, while at the same time the facility of putting the article on or off, obtained by the elastic fastenings, is secured.

The invention consists in closing the slit in a glove by means of an inelastic fastening 40 placed at the wrist of the glove and an elastic fastening between said inelastic fastening and the top of the glove, so that when the inelastic fastening is unloosed the glove can be drawn on without loosening the elastic fastening; and it consists, further, in the special 45 combination of an elastic lace with the said inelastic fastening.

The accompanying drawings, which form a part of this specification, illustrate a glove-

fastening embodying the invention, Figure 1 50 showing a glove with the fastening closed, and Fig. 2 a portion of the same with the fastening open.

A is the body of the glove, provided with an opening of the usual form for allowing the 55 glove to be drawn on the hand and arm of the wearer. Along the sides of the opening are eyelets B. At the wrist, in place of an eyelet, is a button, C, hook, or similar device.

D is an elastic and E a non-elastic lace, the 60 two being knotted together at F, and the other ends provided with knots G, to prevent them from pulling through the end eyelets. The laces pass through the eyelets, as clearly shown in the drawings. 65

In order to put on the glove, the lace E is removed from the button C and the glove drawn over the hand, the lace D stretching as required. When the glove is drawn on, the lace E is caught over the button C and retains 70 the glove closely and firmly at the wrist, preventing it from being drawn off. By detaching the non-elastic lace from the button no hindrance remains to removing the glove. By 75 making the laces longer or shorter the glove can be fitted to different-sized wrists.

Knots may, if desired, be made in the elastic lace at suitable intervals, in order to make it draw more evenly through the eyelets.

Instead of using a non-elastic lace with button, hook, or other holder at the wrist, an ordinary flap with button-hole can be used with a button, a lace to be drawn up and tied, a hook and eye, or other appropriate fastening could be used. More than one catch or fastening could be used. Instead of the elastic lace, which, however, is preferred, and constitutes itself, in connection with the non-elastic fastening, the second part of this invention, an elastic web or fabric could be used. 80 85 90

The term "non-elastic fastening" is applied to the device or devices at the wrist, not as excluding all elasticity, for the lace E could be made elastic without departing from the spirit of the invention, but as indicating that said 95 device or devices do not possess such elasticity as would allow the glove to be drawn over the hand when fastened, and in contradistinc-

tion to the other or elastic part of the fastening, which is extensible, to allow it to be drawn on or off. The elastic lace and non-elastic fastening could be used with other garments than 5 gloves—shoes and corsets, for example.

Having thus described my invention, what I claim is—

1. In a glove, the combination of an inelastic fastening at the wrist and an elastic fastening 10 between said inelastic fastening and the top of the glove, substantially as described.

2. The combination of the elastic lace and inelastic fastening for closing the slit in a glove, arranged and adapted to operate substantially as described.

In testimony whereof I have signed this specification in the presence of two subscribing witnesses.

FRANÇOIS ADOLPHE CHARLES JEAN OMLOR.
